(57) **CLAIM**

The ornamental design for an electronic cigarette as shown and described.

DESCRIPTION

FIG. 1 is a front side perspective view of an electronic cigarette in accordance with my design;
FIG. 2 is a rear side perspective view of the electronic cigarette of FIG. 1.

FIG. 3 is a front elevation view of the electronic cigarette of FIG. 1.

FIG. 4 is a rear elevation view of the electronic cigarette of FIG. 1.

FIG. 5 is a left side elevation view of the electronic cigarette of FIG. 1

FIG. 6 is a right side elevation view of the electronic cigarette of FIG. 1.

FIG. 7 is a top plan view of the electronic cigarette of FIG. 1

FIG. 8 is a bottom plan view of the electronic cigarette of FIG. 1.

FIG. 9 is an enlarged top view of the electronic cigarette of FIG. 1; and,

FIG. 10 is an enlarged bottom view of the electronic cigarette of FIG. 1.

The broken lines shown in the drawings depict portions of the electronic cigarette that form no part of the claimed design.

1 Claim, 10 Drawing Sheets
